UNITED STATES PATENT OFFICE.

JOSEPH EDWARD LORD CLARK AND WILLIAM JOHN KEMP CLARK, OF BRIXTON, COUNTY OF SURREY, AND ROBERT DAVEY BOWMAN, OF LEYTONSTONE, COUNTY OF ESSEX, ENGLAND.

ELECTRIC-ARC LAMP.

SPECIFICATION forming part of Letters Patent No. 324,008, dated August 11, 1885.

Application filed December 15, 1883. (No model.) Patented in England March 5, 1883, No. 1,182.

To all whom it may concern:

Be it known that we, JOSEPH EDWARD LORD CLARK, of Brixton, in the county of Surrey, WILLIAM JOHN KEMP CLARK, also of Brixton, aforesaid, and ROBERT DAVEY BOWMAN, of Leytonstone, in the county of Essex, England, subjects of the Queen of Great Britain, have invented certain new and useful Improvements in Electric-Arc Lamps, (for which we 10 have received Letters Patent in Great Britain, No. 1,182, dated March 5, 1883,) of which the following is a specification.

This invention has for its object improvements in electric-arc lamps; and it consists, 15 essentially, of a method of effecting the feed by operating the upper carbon; and, secondly, in the establishment of the arc by actuating the lower carbon, in combination with such feeding device.

20 The invention will be best understood with reference to the annexed drawings.

Figure 1 gives in a diagram all the electrical connections of parts. Fig. 2 is a plan of this lamp with the cover and part of the framing removed. Fig. 3 is an end elevation, and Fig. 25 4 is an elevation, of the lamp in the normal position; Fig. 5, an elevation at the time of feeding. Fig. 6 is a general side elevation of the lamp mechanism with the terminals for 30 the main circuit, and Fig. 7 is a side elevation of the mechanism operating the lower carbon rod.

Similar letters of reference in different figures indicate corresponding parts.

35 The lamp consists of the mechanism for feeding the upper carbon-holder, which mechanism is contained in the upper casing, and of the mechanism contained in the lower casing for forming the arc when the feed has been 40 effected, said arc being formed by the downward movement of the lower carbon-holder. The mechanism contained in this upper casing, C', of the lamp mainly consists of the electro-magnets j and d, both in a branch circuit. The electro-magnet j operates a pendulum-armature, k, made of iron, which, when 45 in a vertical position, inserts into the circuit the electro-magnet d, by making contact between a spring, i', attached to said pendulum-

armature and between an adjustable screw, l, 50 in an insulated bracket, f. The ends of wire of electro-magnet j are connected, respectively, to a wire, A², which is connected to the negative binding-post B and to the pendulum-armature k. The negative binding-post B is 55 insulated from the lamp-framing; but the positive post A is electrically connected thereto. The said pendulum-armature k is pivoted on a bracket, k², secured to the top of the electro-magnet j, being electrically connected to the 60 said bracket, said bracket itself being in electrical connection to the framing of the lamp and with the positive current therein. The pendulum-armature k is suspended in such a way as to assume an inclined position when 65 not being attracted, and is maintained in this position by means of a flat spring, k³, secured to the back of the flat iron bar k, which spring reaches with the free end over the edge of top face of the electro-magnet j. Another flat 70 spring, i', is secured to the face side of bar k, and makes contact with the point of screw l, but only when the bar k, being attracted by the electro-magnet j, has assumed a vertical position. The fulcrum of bar k is in k', which is a 75 cross-pin. This pin is fulcrumed in U-shaped slots, provided in the bracket k², which is screwed to the top flange of the electro-magnet j. Screw l is screwed into the angular bracket f, which is likewise screwed to the 80 top flange of magnet j, but insulated therefrom. Screw l is electrically connected, by means of a wire, f', to a slender sheet of platinum, x, which is screwed to the lamp-framing insulated therefrom, and which forms a 85 flat spring, against which, under normal conditions—that is, when the carbon rod is locked to a stationary position—the platinum point of a screw, f'', is resting, said screw being electrically connected to end of wire of electro-magnet d, said wire being marked with f³. 90 This electro-magnet d, in shape of a horseshoe-magnet, is insulated from the lamp-framing, and has its wire ends electrically connected to said screw f² and to wire A², which is leading 95 to the negative binding-post B. The electro-magnet d is cut out from or inserted into the circuit by the relative position assumed by

the pendulum-armature *k*, and said magnet *d* actuates the longer end of a pivoted-lever armature, *b*, which carries at said end the said screw *f*². A small strip of metal is screwed 5 rigidly fast to and is insulated from the end of the brass lever of armature *b*, and screw *f*² is tapped into said insulated strip of metal. The lever-armature *b* consists of a bar of wrought-iron secured crosswise underneath 10 a brass bar, which is pivoted between the points of the screws *y*, said screws screwed into the flanges of the U-shaped inverted bracket *a*, which is rigidly fast to the frame of the lamp, and is sleeved over the rod *c* of the upper 15 carbon-holder. The pivoted brass bar is sleeved at its shorter end *b*' over the carbon rod, and is adapted to clutch the same by said sleeved part when the lever-armature is in its normal—that is, in an inclined—position, so as 20 to press screw *f*² against platinum sheet *x*. Said part *b*' is adapted to release the rod *c* again when the lever-armature is in a horizontal position, which occurs when electro-magnet *d* has attracted the same, and when 25 the electrical contact between sheet *x* and screw *f*² is broken.

In order to press the platinum points of screw *f*² against sheet *x*, when the electro-magnet *d* has released the armature *b*, a 30 spring, *e*, is provided thereon and secured to the same between the iron cross-bar and between the pivoted brass bar. Another object of spring *e* is also that it presses with its free end against rod *c*, and serves as a brake in 35 order to check the sudden drop of the armature and to convert it into an easy sliding-down movement underneath the electro-magnet *d*. Another similar spring, *z*, is secured rigidly fast, and also made to bear against the 40 rod *c*, with the object of forming a good electrical connection between lamp-framing and rod of carbon-holder. For the sake of convenient connection of the negative binding-post *B* and the respective ends of wire of electro-magnets *i* and *j*, a wire, *A*², is run down from 45 said post *B* to an insulated post, *B*', on the platform or bed-plate of the lamp, and said post *B*' is electrically connected to the insulated post *B*'. (See Figs. 2 and 6.) The post 50 *B*' is at the top end of a wire or rod, *A*', leading down to the mechanism actuating the lower carbon-holder, as illustrated in Fig. 7.

This mechanism is especially adapted for forming the arc, and consists of an electro-magnet, *m*, of the horseshoe type, which is secured rigidly fast to a plate, *n*², by means of suitable arms or studs, *n*³, one of which is shown partly cut off in Fig. 7. The plate *n*² forms the bed-plate for the mechanism and 55 parts of the lower carbon-holder, and by being sleeved over it guides the same. Said plate also supports the metal cover incasing said mechanism and is secured to the bed-plate of the upper carbon-holder by means of 60 three insulated rods, one of which is marked with *A*'.

The electro-magnet *m* operates on armature

n', which is a cross-bar secured rigidly fast to the rod *q* of the lower carbon-holder *n*, and a helical spring, *p*, is sleeved over rod *q* between the armature *n*' and the connecting-bar of the two cores of the electro-magnet *m*, in order to facilitate the release of said armature from said magnet, and with the object to carry the rod *q* with the lower carbon-holder 70 in its upper position, while the armature *n*' is not attracted by electro-magnet *m*. Suitable adjustable screws screwed into plate *n*² limit the play of the armature, like screw *n*⁴, or guide the same, like screw *n*⁵, the latter 75 screw fitting into a hole drilled into armature *n*'. The wire on the electro-magnet *m* is electrically connected with one end, *r*, to the plate *n*², and is therefore also in electrical connection with the lower carbon-holder, *n*, and with 80 the other end, *r*', the wire of said magnet is connected to the rod or wire *A*'.

The action of the whole lamp will be as follows, (see Fig. 1:) Suppose the two carbon points be at a distance of several inches from each other, the current will enter at binding-post *A*, will go down the casing of the lamp into the frame and into the pendulum-armature *k*, and through the coil of electro-magnet *j* into wire *A*² and the negative post *B*. The pendulum-armature will thereby make at once contact between spring *i*' and screw *l*. Screw *f*², however, and sheet *x* are already in contact with each other, because the lever-armature *b* is in an inclined position, whereby also the carbon 90 rod *c* is locked into a stationary position. The current, therefore, is established from the positive post *A* and from the electro-magnet *j* to the pendulum-armature *k*, and to spring *i*' to screw *l*, and by means of wire *f*³ to electro-magnet 95 *d*, and therefrom to wire *A*² and negative post *B*. Armature *b*, however, will be attracted, which causes rod *c* to slide down, and the contact between sheet *x* and screw *f*² is simultaneously broken, armature *b* will be released 100 and will swing upward again. Stopping again 105 rod *c* a vibratory movement of armature *b* will be made, which causes rod *c* to be fed slowly until the two carbons meet, electro-magnet *j* always serving as a constant resistance for the current during the alternate inserting and cutting out of magnet *d*. As soon 110 as the carbons meet the current will run down the same and go through the electro-magnet *m*, because the latter offers less resistance than 115 magnet *j* alone. Contact of sheet *i*' with screw *l* will therefore be also broken at once, and as no current is in magnet *d* the rod *c* will be clutched by the lever-armature *b*. The current will now run through the carbons and 120 wire *v* into electro-magnet *m*, which has coarse wire, and through wire *o*' into rod *A*' to post *B*', from there to post *B*', and through wire *A*² to the negative post *B*. Armature *n*' will 125 therefore be attracted, and the carbon rod *q*, with lower carbon-holder, *n*, will move downward, so as to form the arc between the two carbon points. According to the decrease or 130 increase of resistance in this arc, more or less

current, respectively, will go through magnet *j* and also through magnet *d*, or also more or less current, respectively, will go through magnet *m*. The arc therefore may be regulated at 5 will by suitable adjustment of screws *l*, *f*², and *n*⁴.

We are well aware that lamps have been constructed with mechanism for moving the lower carbon separately. We do not claim such mechanism in general, but simply the particular combination and construction shown and described; also, we disclaim the manner of clutching the carbon rod by means of a ring-shaped lever, because it is not new to construct lamps with jambing-rings for clutching and releasing the upper carbon rod.

What we claim, however, as new, and wish to secure by Letters Patent, is—

In electric-arc lamps, the combination, with 20 the upper carbon rod, of a feeding mechanism consisting of two electro-magnets, as *j* and *d*, both in shunt-circuits, a pendulum-armature, as *k*, suspended above one of said electro-magnets, with a contact-spring, *i*', and a restraining-spring, *k*³, attached thereto, said armature 25 electrically connected to the coil of said electro-magnet and to the framing of the lamp, a contact-screw, *l*, mounted on an insulated bracket opposite of said armature and electrically connected to an insulated contact-sheet 30 *x*, a fulcrum-lever, as *b*, and a spring, as *e*, se-

cured thereto, which bears against the carbon rod, a clutch-ring, as *b*', integral with said lever, and an armature-bar attached thereto for the other electro-magnet, an insulated contact-screw mounted on said lever and electrically connected to the said other electro-magnet, the positive binding-post *A*, electrically connected to the carbon rod, the negative post *B*, electrically connected to one end of each 40 electro-magnet, the combination, with the lower carbon rod, *q*, which is sleeved in the framing, of mechanism for drawing the arc, consisting of a coarse-wire magnet, as *m*, which is electrically connected with one wire end to the 45 lower carbon rod, and with the other end to the negative binding-post, by means of the connections *o*' *A*' *B*' *B*² *A*², an armature, as *n*', attached to the lower carbon rod, a helical spring, as *p*, sleeved over said rod and supporting the same with said armature, the guiding-screw *n*⁵, sleeved into said armature, and the screw *n*⁴, limiting the play of the same upward, all for the purpose set forth, and substantially as shown and described.
